UNITED STATES PATENT OFFICE.

JOHN ASBURY SMITH, OF HARRISBURG, PENNSYLVANIA, ASSIGNOR TO ELLIOTT-FISHER COMPANY, OF NEW YORK, N. Y., A CORPORATION OF DELAWARE.

REGISTER FOR ADDING-MACHINES.

1,114,056.

Specification of Letters Patent. Patented Oct. 20, 1914.

Application filed December 14, 1907. Serial No. 406,482.

To all whom it may concern:

Be it known that I, JOHN ASBURY SMITH, a citizen of the United States, residing at Harrisburg, in the county of Dauphin and State of Pennsylvania, have invented a new and useful Register for Adding-Machines, of which the following is a specification.

This invention relates to a totalizer or register and more particularly to a mechanism of this character adapted for use in a combined typewriting and calculating machine, such for instance as the Elliott-Fisher billing machine of commerce, exemplified in Patents Nos. 820,879 and 829,971 to 15 Laganke and Smith.

It may be stated by way of introduction, that the totalizer or register, shown in the patents identified, is adapted for uniform addition, that is to say, addition in which 20 the various denominations, in which the value is embraced, each have the same numerical limit of value, as for instance the decimal system, wherein the unit of value of each denomination is ten times the unit 25 value of the denomination of next lower order. It has been proposed, however, to arrange totalizers, of the character under consideration, for non-uniform addition, that is to say, addition wherein the limits 30 of value of the several denominations are different, for instance pints, quarts and gallons, wherein the limit of value of the pints denomination is two, of the quarts denomination four, and of each gallon denomination ten.

Several of the constructions proposed for facilitating non-uniform addition are shown in my co-pending application No. 404,020. In such proposed constructions, however, 35 the desired result is attained by utilizing number wheels of different diameters, eccentrically mounted with respect to each other, upon separate eccentrically arranged shafts extending in opposite directions from a partition which subdivides the register casing into separate compartments. The stated characteristics of the registers devised for non-uniform addition constitute material 45 variations from the standard Elliott-Fisher 50 totalizer construction, in which, as shown in the patents identified, all of the number wheels are mounted on the same shaft and are of uniform diameter.

It is obviously desirable, in the economy 55 of manufacture, to have all registers as near

a common standard of construction as possible.

To this end the object of the present invention is to produce a totalizer adapted for the performance of non-uniform addition 60 without necessitating the employment of number wheels of different diameters or eccentrically mounted.

Another object of the invention is to produce a totalizer adapted for the automatic 65 addition of minutes and hours, as numbers representing minute and hour values are typewritten in a column.

To the accomplishment of these objects and others subordinate thereto, the preferred embodiment of the invention resides 70 in those features of construction and arrangement to be hereinafter described, illustrated in the accompanying drawings, and succinctly defined in the appended claims. 75

In said drawings—Figure 1 is a front elevation of the register. Fig. 2 is a similar view with a portion of the register casing removed to facilitate the disclosure of hidden parts. Fig. 3 is a vertical sectional view 80 of the same. Fig. 4 is a plan view of the major portion of the mechanism housed in the register casing, the front wall of the latter being shown in section. Fig. 5 is a longitudinal sectional view 85 on the line 5—5 of Fig. 3. Fig. 6 is a section on the line x—x of Fig. 3, looking in the direction indicated by the arrow. Fig. 7 is a longitudinal section on the line y—y of Fig. 3, looking in the direction indicated by 90 the arrow. Fig. 8 is another longitudinal section on the line z—z of Fig. 3, looking to the right as indicated by the arrow, and Fig. 9 is a detail perspective view of the tens of minutes wheel. 95

Each part, wherever shown, is indicated by the same reference character.

As already stated, the totalizer, register or computing device to be described is intended for use as a part of a combined typewriting and adding machine the keys of which operate the printing mechanism to print numbers in a column, and also cause the simultaneous operation of a master means which is presented, by the movement 100 of the typewriter carriage, in co-operative relation with successive denominational members of the computing device. In certain aspects of the invention, however, it involves patentable novelty which relates 105 110

solely to the adding mechanism, and which, while especially useful in the specified relation, is susceptible of use in machines other than combined typewriters and adders.

- 5 As will be understood by those skilled in the art, the mechanism, known variously as the totalizer, register, or computing device, is ordinarily mounted on the machine frame of an Elliott-Fisher typewriter and is disposed for actuation by a master wheel mounted on the carriage of the typewriter and rotatable different distances upon the depression of the numeral keys. A register supporting bar 1' is shown in Figs. 6 to 8 10 inclusive of the drawings. The register, supported upon this bar and shiftable along the same to different column positions, embraces a casing 1, within which the computing and registering mechanism is assembled. 15 In the present instance this mechanism is designed to add minutes and hours and to register the total in view of the operator of the typewriter so that the result may be typewritten at the foot of the column without necessity for mental calculation.

In the upper front corner of the casing is mounted a transverse shaft 2. This shaft is journaled in the opposite side walls of the casing and is passed through a partition 3 which subdivides the casing into left and right hand compartments 4 and 5. A similar shaft 6 is located below the shaft 2 and is likewise journaled in the side walls of the casing. These shafts support certain operating elements located in both the left and right hand compartments 4 and 5. The mechanism located in the left hand compartment is not novel, but will be first described, as a thorough understanding of what is old in the art will materially aid in the comprehension of the novel features which have been introduced in the register construction for the purpose of accomplishing non-uniform addition. Proceeding then to describe the mechanism in the left hand compartment 4, a series of identical, uniformly-spaced denominational members or number wheels c' , d' , e' , f' , g' and h' are rotatably mounted on the number wheel shaft 2, to the left of the partition 3, and are formed with ten peripheral teeth upon the outer faces of which are displayed the digits 0 to 9 inclusive. In the present instance these wheels represent units, tens, 50 hundreds, thousands, ten-thousands, hundred-thousands and millions of hours and may be termed collectively the hours wheels.

On the shaft 6 at the left of the partition 3 are mounted a corresponding series of operating wheels or idlers c , d , e , f , g and h , each of which meshes with one of the superadjacent number wheels and is adapted to be engaged and rotated by a master wheel M, for the purpose of transmitting motion 60 from said master wheel to the respective

number wheels c' , d' , etc. As is well understood in the art, the master wheel engages the several idlers in succession as the printing point of the typewriter moves from one denominational position of the column to another. As a digit is printed in a given order of the column the master wheel is rotated a number of increments, or units of movement, corresponding to the value of the digit, thus causing the number wheel of corresponding denominational position to be rotated a corresponding number of increments, for the purpose of accumulating upon said wheel the value of the digit printed. Coöoperating with each of the operating 70 wheels or idlers c , d , etc., is a spring-urged locator 7 which tends to accurately position these wheels so that their teeth will be normally located in alinement to facilitate the lateral passage of the master wheel across the series of idlers.

The carrying mechanism for the hours wheels.—It will of course be understood that a mechanism of this character necessarily embodies carrying mechanism, that is to say, 80 mechanism whereby, when any given wheel has accumulated the limit of value of that particular denomination, such value will be carried or transferred to the adjacent wheel of higher order. For this purpose a series 90 of carrying levers 8 are fulcrumed on a rod 9 extending transversely of the casing adjacent to its lower rear corner, see Fig. 5. Each of these levers 8 has a depending short arm 10 connected to one end of a spring 11 100 the opposite or rear end of which is secured to a fixed part of the casing. The spring 11 tends constantly to draw the short arm 10 of the lever rearwardly and thus cause the long arm 12 of said lever to swing downwardly.

The forwardly disposed long arm 12 of each carrying lever 8 is bifurcated to form a locking end 13 and a guide lug 14. The end 13 is designed to engage between two teeth 110 of the adjacent idler to lock the latter when the lever is swung down, and the lug 14 is guided in a kerfed guide-bar 15 to prevent lateral movement of the lever. From the locking end or arm 13 of the lever 8 is 115 swung a carrying dog 16 designed to extend over a tooth of the operating wheel or idler served or operated by the lever. Thus when the lever is operated, its transfer dog, by reason of its engagement with a tooth of the 120 adjacent idler, will advance said idler one increment or unit of movement and thus effect a similar advance of the number wheel engaged by said idler.

The operation of each transfer lever 8 is 125 controlled by a selector 17 which is operated by the adjacent wheel of lower order. The selectors 17 are in the form of substantially triangular swinging plates pivoted upon a transverse bar 18 and yieldingly re- 130

tained in normal position by springs 19, as clearly shown in Fig. 5. The lower end 20 of each selector extends under the lower edge of the adjacent transfer lever 8 to the left of the selector and thus holds the lever normally elevated. Each lever 8 is provided, however, with a cut-out portion or notch 21 in its lower edge and this notch is so located that when the adjacent selector 17 is swung back, its inturned edge 20 will come opposite the notch in the lever and thus allow the lever to drop for the purpose heretofore stated.

Each selector 17 is arranged to be operated by the adjacent idler to the right of the selector. The selectors 17 are mounted opposite the spaces between the idlers *a*, *b*, etc., and each has a forwardly extended contact plate 22 located between two adjacent wheels and arranged to be operated by a carrying lug 23 extended laterally from the idler to the right of the selector. Each idler *a*, *b*, etc., is provided with a single transfer or carrying lug 23 and this lug is so located that when the number wheel engaged by the idler moves from 9 to 0, or in other words, reaches the limit of its value, the lug will engage the contact plate 22 of a selector and thus swing the latter back. This backward movement of the selector will effect the release of the transfer lever to the left thereof and said transfer lever will swing down under the impulse of its spring 11 and will, through the medium of its transfer dog 16, rotate the next adjacent idler to the left a single increment, thereby causing said idler to advance or carry the adjacent number wheel one unit of movement to accumulate thereon the value represented by one complete rotation of the wheel of next lower order. In other words, when the units wheel *c*, for instance, has been operated nine increments, and thus displays "9" at the sight opening, the next increment of movement of said wheel will display the 0 thereon at the sight opening and will cause the operation of a selector 17 to release a transfer lever 8 and thus cause said transfer lever to advance the number wheel of next higher order, to-wit, the tens wheel *d*, one increment, to present the 1 thereon at the sight opening and thus cause the registration of "10", which is the limit of value of the wheel *c*. The wheel *c* may then be operated independently for nine additional increments, and upon the next increment will again cause the next higher wheel *d* to be advanced, and so on indefinitely, each wheel carrying to the next when its limit of value is reached.

60 The transfer dogs 16 necessarily have sufficient backward movement to prevent them from obstructing the further movement of an idler which has been advanced by the dog. It is usual therefore to provide vibrators 24 mounted on a transverse rod 25

and engaging the lower ends of the dogs 16 to urge the same into engagement with the wheels *a*, *b*, etc., at the proper time. These vibrators are usually extended through the front of the casing 1, as shown, and their forwardly extended ends 26 are depressed by a part carried by the typewriting carriage, in a manner in which those familiar with the art are acquainted.

The means for restoring the carrying levers and selectors to normal position.—This mechanism constitutes no part of my present invention, except in so far as it may enter into novel combination with features to be described. In order that the entire mechanism of the register may be fully comprehended, however, it may be stated that a restoring rocker 27 is swung from a bar 28 extended transversely of the casing and is geared to a slide 29 automatically operated upon the retraction of the typewriter carriage to swing the rocker 27 and cause the same to elevate or reset the carrying levers 8 and to swing the selectors 17 to their set positions.

The means for resetting the hours wheels to zero.—After a computation has been effected, it is necessary to clear the register, that is to say, the number wheels must be reset to zero in order that another computation may be effected. To accomplish this purpose, a resetting lever 30 is mounted at the left hand side of the casing and is provided at its rear end with a handle 31 by which it may be manipulated. At the front end of the lever 30 is a segmental rack 32 which meshes with a gear wheel 33 fixed to the shaft 6, see Figs. 3, 4 and 5. Also fixed to the shaft 6, are a series of resetting cams 34 which alternate with the wheels *c*, *d*, etc., and are formed with shoulders 35. Upon the left hand face of each wheel *a*, *b*, etc., is mounted a resetting dog 36 urged against the periphery of an adjacent cam 34 by a spring 37. The shaft 6 and the cams 34 thereon are normally stationary. Therefore, as the primary or operating wheels *c*, *d*, etc., are rotated during the operation of the register, the resetting dogs 36 thereon merely travel idly around the cams 34. These dogs in the normal or zero positions of the wheels are located just in advance of the shoulders 35 of the resetting cams, which shoulders are alined. Therefore, when it is desired to reset the register, the handle 31 is grasped by the operator and the resetting lever 30 is swung in a manner to cause the rack 32 to rotate the gear 33 which, being fixed to the shaft 6, rotates the latter and the cams 34 thereon. This rotation of the cams will cause the shoulders 35 thereof to engage the dogs 36 on the adjacent wheels *a*, *b*, etc., and as the shaft is given slightly more than a complete rotation, the wheels *c*, *d*, etc., will be rotated to reset the regis-

tering wheels c' , d' , etc. Having reset the register, the lever 30 is swung back to its normal position, the shaft 6 and the resetting cams 34 being reversely rotated to normal position independently of the wheels. It usually happens that when it is desired to reset the register one or more of the transfer levers 8 will be in their depressed or operated positions and one or more of the wheels will therefore be in locked condition. As the wheels must be unlocked before they can be reset, the lever 30 is provided with a cam 38 coacting with a slide retracting lever 39 operatively connected to the slide 29 and urged in one direction by a spring 40. The initial movement of the resetting lever 30 causes the cam 38 to operate the lever 39 to retract the slide 29, which in turn causes the rocker 27 to reset the transfer levers 8 and selectors 17, the parts being so timed that the locking ends 13 of the transfer levers 8 will release the primary wheels a , b , etc., before any of the resetting dogs 36 are picked up by the cams 34. It has already been explained that the movement of the wheels from 9 to 0 effects the operation of the selectors 17 and transfer levers 8 to carry values from one denomination to another. It follows that this action will also take place just before the wheels reach their fully reset positions and consequently when the wheels have been reset they will be in locked condition, since the levers 8 will be depressed. Therefore, mechanism is provided, whereby after the rocker 27 has been operated by the initial movement of the resetting lever 30 to reset the transfer levers 8 and the selectors 17, said rocker will move back slightly so as to allow the backward swinging of the selectors by the wheels during the resetting thereof, without, however, permitting the transfer levers to drop when released by the selectors. The mechanism to which reference has just been made is so arranged that upon the retraction of the wheel resetting lever 30, the rocker 27 will be permitted to again move forward to reset the selectors which have been swung back during the resetting operation, after which said mechanism, which is in effect a stop mechanism, will be operated by the resetting lever to permit the rocker and its associated parts to be wholly retracted to normal position. The stop mechanism, which coöperates with the rocker 27 and the resetting lever 30, is clearly shown in Fig. 6 of the drawings, and includes a vertically reciprocatory stop 57 coöperating with a pin or stop 58 projecting from one side of the lever 39. The stop 57 is carried at the lower end of a slide 59, held against the left hand wall of the casing by a suitable retainer 60 and normally engaged and held depressed by the lever 30 against the resistance of a spring 61.

This mechanism is fully described and claimed in my co-pending application No. 404,020 and constitutes no part of my present invention, except in so far as it may enter into novel combination with the distinguishing features of the register described herein. The various positions of the parts during the resetting operation have therefore not been illustrated, and the following brief description of the operation will therefore suffice.

When the resetting lever 30 is thrown up it will operate the lever 39, which in turn will operate the rocker 27 to reset such of the transfer levers and selectors as may have been left in operated condition at the completion of the last computation. Incidental to this operation the pin 58 on the lever 39 will have moved back beyond the stop 57 and said stop will have been elevated by the spring 61 to a position in advance of the stop. As the elevation of the lever 30 is continued to reset the wheels, said lever will move out of coaction with the lever 39 and thus permit the spring 40 to swing the lever 39 in a forward direction until the pin 58 is arrested by the stop 57. This limited movement of the lever 39 will cause it to slightly retract the rocker 27, such retraction being just sufficient to permit the selectors to be swung back during the resetting of the wheels without removing the rocker from its supporting position beneath the transfer levers 8. As the resetting lever completes its upward excursion, the movement of the wheels from 9 to 0 will throw back the selectors, which obviously must be reset before the register can be again operated to effect a computation. Therefore, as the resetting lever 30 is retracted toward its normal position, it will again coact with the lever 39 moving the pin 58 back from the stop 57 and thus causing the rocker 27 to be operated to reset the selectors 17. Continued retractile movement of the lever 30 will move it out of coactive relation with the lever 39 and will depress the stop 57 out of the path of the pin 58 and thus allow the spring 40 to restore the lever 39, the slide 29, and the rocker 27 to normal position.

The mechanism thus far described is that which is housed in the left hand compartment 4 of the casing and is adapted for what I term uniform addition, since the several denominations of hours, as for instance units, tens, hundreds, etc., of hours, have uniform limits of value, the value of each denomination being ten.

The mechanism in the right hand compartment of the casing, to-wit, the minutes wheels and their coöperating parts.—I shall now proceed to describe the mechanism housed within the left hand compartment 5 of the casing. This mechanism includes the units and tens of minutes wheels a' and b' ,

both of which are mounted on the right hand end of the shaft 2 and are of the same diameter as the hours wheels c' , d' , etc. The units of minutes wheel a' is in all essential particulars like the hours wheels. It is mounted loosely on the shaft 2, has ten peripheral teeth bearing the digits 0 to 9 inclusive, and meshes directly with a primary wheel or idler a on the shaft 6.

10 The tens of minutes wheel b' differs materially both in construction and mounting from the other registering wheels. This wheel, while of the same diameter as the other registering wheels, is not peripherally toothed, and instead of bearing a single series of ten digits, has displayed upon its periphery two series of digits each ranging from 0 to 5 inclusive. This wheel is therefore what may be termed a twelve-increment wheel, as distinguished from the other registering wheels, all of which have ten increments or units of movement during each complete rotation thereof. The reason for this variation between the tens of minutes 25 wheel and the other registering wheels is that the limit of value of the tens of minutes denomination is six instead of ten, and as it is not desirable to utilize a six-increment wheel, a twelve-increment wheel is utilized 30 and is made to carry twice for each complete rotation thereof. Nevertheless, the wheel b' must be operated by its primary wheel or idler b and said idler must correspond to the other idlers in order to accommodate the 35 same master wheel. As each idler is a ten-increment wheel, that is to say, advances ten units of movement for each rotation, and as the tens of minutes wheel b' is a twelve-increment wheel, and is nevertheless of the 40 same diameter as its idler, it follows that a train of gearing must be utilized to communicate motion from the idler b to the wheel b' in order that when the idler is advanced one increment, corresponding to one-tenth of its rotary movement, the tens of 45 minutes wheel b' will be rotated a single increment, corresponding to one-twelfth of its complete movement. For this reason the idler b is mounted upon the hub of a gear 50 wheel 41 disposed closely adjacent to the right hand side of the partition 3, while the wheel b' is similarly fixed upon the hub of a gear wheel 42 similarly disposed adjacent to the partition. The gears 41 and 42 are of 55 different diameters and bear the relation of ten to twelve, the gear 41 preferably having fifteen teeth and the gear 42 eighteen teeth, as shown in Fig. 6. The gears 41 and 42 are geared together by means of an idle gear: 60 43 mounted on a stud shaft 44 screwed into the partition 3, the size of this gear being immaterial.

It will now be seen that upon the rotation of the idler b any given number of increments, the tens of minutes wheel will be

rotated a like number of increments, notwithstanding the fact that the units of movement of these wheels differ in extent. It will also be noted that by reason of the interposition of the idle gear 44 the wheel b' 70 will be rotated in a direction opposite to the direction of rotation of the other registering wheels, all of the primary wheels or idlers a to h inclusive being rotated in a uniform direction when operated by the master 75 wheel. Attention is also directed to the fact that by reason of the interposition of the gear 42 and the partition 3 between the wheels b' and c' , these wheels are separated by a distance equal to a letter space of the 80 typewriter and that the wheels a' and b' are similarly spaced apart by a spacing collar 45 and a reset cam, which will be presently described. Furthermore, the fact that the wheels b and b' are not directly geared 85 makes it necessary to offset the primary wheel or idler b to one side of the wheel b' and this requisite, in connection with the space occupied by the gearing and the partition, separates the wheels b and c by an interval equal to two letter spaces of the typewriter machine. In writing, however, there will not be a space between units and tens of minutes, since the wheels a and b occupy adjacent letter space positions, but 90 two spaces will occur between tens of minutes and hours, so that the reading of the number will be properly facilitated.

The means for carrying from units to tens of minutes and from tens of minutes to hours.—The means whereby the limit of value is carried from the units of minutes wheel a' to the tens of minutes wheel b' is precisely like the carrying mechanism heretofore described, a transfer lever 8 being 100 arranged opposite the idler b and being controlled by a selector 17 operated by a lug on the idler a . Therefore, in transferring from the wheel a' to the wheel b' , there is absolutely no difference, either in the construction or operation of the mechanism, from a similar function to effect carrying from one hour wheel to the next, except for the fact that the idler b , when operated by the transfer lever 8, does not directly advance the wheel b' , but causes the advance 110 of the same through the intermediate gearing 41, 42 and 43.

The operation of carrying from the tens of minutes wheel b' to the units of hours 120 wheel c' is different. This is principally for the reason that the transfer lever for the wheel c' obviously cannot be controlled from the idler b , but must be controlled from the wheel b' . This mechanism will be 125 understood by reference more particularly to Fig. 6. The transfer lever 8 for the units of hours wheel c' is precisely like the other transfer levers and operates in exactly the same manner when released to advance the 130

idler c and its number wheel c' one increment. The selector 17^a for this lever is somewhat different from the selectors described, in this, that it has a forwardly extended end 46 deflected laterally through an opening 47 in the partition 3, see Figs. 4 and 6, and having its extremity 48 located in the path of two triangular carrying lugs 49 and 50 which project laterally from the left hand side face of the tens of minutes wheel b' , see Figs. 2, 3, 6 and 9. During the sixth increment of movement of the wheel b' and also during the final or twelfth increment of movement thereof, or in other words, whenever said wheel moves from 5 to 0, the value accumulated thereon will be transferred to the units of hours wheel c' , since one of the lugs 49 or 50, as the case may be, will depress the forward extremity 48 of the selector 17^a and will cause the same to release the transfer lever of the wheel c' .

The resetting of the minutes wheels.—The resetting of the minutes wheels is effected simultaneously with the resetting of the hours wheels by the manipulation of the resetting lever 30. The mechanism whereby the manipulation of this lever effects the resetting of the units of minutes wheel a' is identical with that heretofore described for resetting the hours wheel. That is to say, a resetting cam 34, mounted on the shaft 6, picks up a dog 36 on the idler a and thus rotates said idler to cause the same to reset the units of minutes wheel a' in mesh therewith. The tens of minutes wheel b' , however, cannot be reset in this manner from its idler, because one complete rotation of the idler would only effect ten-twelfths of a complete rotation of the wheel b' . Therefore special provision is made for resetting the wheel b' .

On the right hand side face of the wheel b' is mounted a resetting dog 51 similar to the dogs 36 and arranged to be picked up by a resetting cam 52 fixed to the registering wheel shaft 2 between the wheel b' and the spacer 45. The right hand ends of the two shafts 2 and 6 are geared together by gears 53, 54 and 55, see Fig. 8, so proportioned that when the shaft 6 is rotated by the manipulation of the resetting lever 30 the shaft will be rotated in like degree and in the same direction through the medium of the gearing. It follows that when the resetting lever 30 is operated, the registering wheels a' , c' , d' , e' , f' , g' and h' will be reset by their idlers which are picked up by resetting cams on the shaft 6, while the tens of minutes wheel b' will be reset by the cam 52 on the number wheel shaft 2, this resetting movement of the wheel b' , like the operating movement thereof, being in a direction opposite to the direction of movement of the other number wheels. It may be in-

cidentally remarked that the lower ends of 65 the several selectors 17 are retained against lateral movement by the transfer levers 8 located at opposite sides thereof, see Fig. 4, and in order to prevent lateral movement of the selector for the transfer lever at the 70 extreme right hand end of the series, a guide-bar 56 is provided at the right hand side of the selector, as shown in Fig. 8. It will, of course, be understood that in the 75 operation of resetting the register the rocker 27 coacts with the entire complement of transfer levers 8 and selectors 17 and 17^a, precisely in the manner heretofore described in connection with the mechanism located 80 exclusively in the left hand compartment of the casing.

Brief summary.—To briefly summarize, the described register is designed for the addition of minutes and hours, the registering wheels representing units of minutes, 85 tens of minutes, and units, tens, hundreds, thousands, ten-thousands and hundred thousands of hours. Each of these denominations has a limit of value of ten except the tens of minutes wheel b' , the limit of value 90 of which denomination is six. Therefore, when ten units of minutes are accumulated upon the units of minutes wheel a' the value is transferred from said wheel to the tens of 95 minutes wheel b' , and when six tens of minutes have been accumulated on the wheel b' , the value thereof, which is one hour, is transferred to the units of hours wheel c' . Similarly, when ten units have been accumulated 100 on any hours wheel, the limit of value of the particular denomination represented by that wheel is transferred to the hour wheel of next higher order. It is to be understood, however, that the master wheel operates any 105 one of the several registering wheels through the primary wheels a , b , etc., the value of the digit printed in any denomination being simultaneously accumulated upon the registering wheel occupying a corresponding denominational position.

It is thought that from the foregoing, the construction and operation of this register will be fully comprehended, but while the present embodiment of the invention is thought at this time to be preferable, I wish 115 to be understood as reserving the right to effect such changes, modifications, and variations of the illustrated structure as may come fairly within the scope of the protection prayed.

What I claim is:—

1. In a register of the character described, the combination with an aligned series of registering wheels, of an aligned series of operating wheels geared thereto, the gearing 125 between certain of the wheels being of different ratios, carrying devices arranged to engage and advance the operating wheels,

- and selectors for the carrying devices, certain of said selectors being operable by certain of the operating wheels and one of said selecting devices being operable by a registering wheel.
2. In a register of the character described, the combination with an alined series of registering wheels, of an alined series of operating wheels geared thereto, the gearing between one of said operating wheels and its registering wheel constituting a reducing train, carrying devices arranged to engage and advance the operating wheels, a series of selectors for said carrying devices, carrying lugs movable with certain of the operating wheels to operate certain of the selectors, and a carrying lug movable with the registering wheel which is operated by the reducing gearing, to operate another selector.
- 10 3. The combination with an alined series of registering wheels, of an alined series of operating wheels geared thereto, carrying devices arranged to engage and operate the operating wheels, and selectors for the carrying devices, each of certain of the operating wheels having a single carrying lug arranged to operate a selector, and one of the registering wheels having a plurality of carrying lugs arranged to operate another of the

- selectors.
4. In a register of the character described, the combination with two parallel shafts, of a series of registering wheels mounted on one shaft, a series of operating wheels mounted on the other shaft and geared to the registering wheels, and resetting mechanism including means whereby different registering wheels will be reset, one through the medium of its operating wheel and another independently of its operating wheel.
5. In a register of the character described, the combination with two parallel shafts, of a series of registering wheels mounted on one shaft, a series of operating wheels mounted on the other shaft and geared to the registering wheels, the gearing between certain registering wheels and their operating wheels differing in ratio, resetting means arranged to rotate both shafts, resetting dogs carried by certain of the operating wheels, resetting cams carried by one of the shafts and arranged to engage said dogs, a resetting cam carried by the other shaft, and a resetting dog carried by one of the registering wheels
- in position to be engaged by said last named resetting cam.
6. In a register of the character described, the combination with an alined series of registering wheels, of an alined series of operating wheels arranged to transmit motion to the registering wheels, a train of reducing gearing between one of the registering wheels and its operating wheel, and carrying mechanism including a plurality of carrying lugs mounted on said registering wheel, a selector successively operated by said lugs, and a carrying lever controlled by said selector and arranged to engage and operate one of the operating wheels.
7. In a register, the combination with a casing divided into two compartments, a series of registering wheels mounted in the first compartment, a series of operating wheels therefor, a registering wheel mounted in the second compartment, an operating wheel therefor, the units of movement of all of said registering wheels being uniform, a second registering wheel in the second compartment, an operating wheel arranged to impart to the last named registering wheel a unit of movement different from the units of movement of the other registering wheels, a resetting device operative to reset all registering wheels having uniform units of movement through the medium of their operating wheels, and means operated by the resetting device to reset the other registering wheel without the interposition of its operating wheel.
8. In a register, the combination with a series of registering wheels, certain of which have uniform units of movement different in extent from the units of movement of another wheel, operating means for the registering wheels, a resetting device operative to reset, through the medium of their operating wheels, those registering wheels which have uniform units of movement, and means operated by the resetting device to reset the other registering wheel independently of its operating wheel.
- In testimony that I claim the foregoing as my own, I have hereto affixed my signature in the presence of two witnesses.
- JOHN ASBURY SMITH.
- Witnesses:
- P. H. TURLEY,
R. C. SMITH.
